(57) **CLAIM**

An ornamental design for a rectangular duffle bag, as shown and described.

DESCRIPTION

FIG. 1 is a perspective view of a new design for a rectangular duffle bag;

FIG. 2 is a rear view thereof;

FIG. 3 is a front thereof;

FIG. 4 is an enlarged right view thereof;

FIG. 5 is an enlarged left view thereof;

FIG. 6 is a top thereof; and,

FIG. 7 is a bottom view thereof.

The broken lines shown in the drawings depict portions of the rectangular duffle bag that form no part of the claimed design.
